UNITED STATES PATENT OFFICE

GEORGE AJDUKOVICH, OF ST. LOUIS, MISSOURI

NECKTIE

Application filed February 7, 1929. Serial No. 338,238.

This invention relates to improvements in ready-made neckties and more particularly to that type of tie known as four-in-hand ties.

One of the objects of the present invention is to provide an improved tie of the above general character, which may be inexpensively manufactured and assembled, as well as conveniently put on and taken off.

A further object is to provide a tie of the above general character provided with securing means which will cooperate with the fabric of the tie to hold the same in predetermined form and shape.

A further object is to provide a device of the last above mentioned character free from objectional projections which might injure the hands or neck of the wearer, as well as prevent unsightly appearance to the finished tie or tend to cause a wearing of the fabric associated therewith.

Other objects will be in part obvious from the annexed drawing and in part hereinafter indicated in connection therewith by the following analysis of this invention.

This invention accordingly consists in the features of construction, combination of parts and in the unique relation of the members and in the relative proportioning and disposition thereof, all as more completely outlined herein.

To enable others skilled in the art to fully comprehend the underlying features thereof that they may embody the same by the numerous modifications in structure and relation contemplated by this invention, drawings depicting a preferred form of the invention have been annexed as part of this disclosure, and in such drawings, like characters of reference denote corresponding parts throughout all of the views, of which—

Fig. 1 is a front elevational view of the complete article showing certain parts of the forming and securing means in dotted lines;

Fig. 2 is a plan view of the sheet metal blank from which the combined former and securing device is made;

Fig. 3 is a rear elevational view of the finished article made from the blank shown in Fig. 2.

Referring now to the drawing in detail

and more particularly to Fig. 1, 5 indicates the knot of usual well known style of four-in-hand tie, and 6 the downwardly extending end. This knot and end 6 are preferably preformed from a single piece of material wound or knotted about a former frame and securing device indicated in dotted lines at 7. The tie is provided with a neck encircling band 8 of the same material and of any desired size having at its free end 10 an elastic tape 11 to which is secured an eye-member 12 adapted to coact with a hook 13 preferably integral with the cooperating fastening and frame device 7. The elastic, of course, permits a certain amount of adjustability in size according to the size of the neck band or collar of the wearer.

The former 7 shown in blank form in Fig. 2 is preferably made of relatively thin sheet metal or celluloid and comprises an angular or L-shaped body portion 7 which has one laterally extending arm 14 terminating in the hook portion 13 and having a lateral reinforcing part 15 adapted to be bent or rounded over longitudinally along the line 16. When assembled, this line 16 is at the top of the tie and provides a smooth rounded edge over which the end 6 passes before being passed down thru the knot 5, thus providing a form free from projections.

The opposite or downwardly extending arm 17 is preferably provided with two laterally extending parts 18 and 20 which are respectively folded easily over towards each other along the lines 21 and 22. These lines 16, 21 and 22 are not sharp folds, but gradually rounded folds, thereby producing an article free from sharp edges as shown more clearly in Fig. 3. In other words, the parts 17, 18 and 20 form almost a frusto-conical frame member extending downwardly into the knotted portion of the tie as shown in Fig. 1, thereby to give it body and appearance as well as being free from any projecting edges or sharp corners which would tend to show through the fabric of the tie and cause wear at such particular projecting points; in fact the overlapping parts 18—20 are on the inside of the knot. Likewise the upper edge of the former, that is, the line 16, is rounded

so as to be U-shaped in cross section on the outer or exposed edge for the same purpose as above explained.

The hook 13 is bent backwardly over the 5 parts 14, 15 and in the finished article this extends just short of one side of the knot to cooperate with the eye 12. In that way, the fastening members 12 and 13 are concealed from view, and it is difficult, if not 10 impossible, to detect the fact that the tie is ready-made instead of hand formed.

The forming frame and fastening device 15 may be relatively inexpensively manufactured by a simple stamping and rolling process, and then assembled in the tie as the same is tied. The shape of the frame member as shown in Fig. 3 makes it especially adaptable to ties of this character in that it automatically retains its position within the knot 20 without other securing or stitching means.

From the above, it will be seen that the present invention provides a simple and practical four-in-hand necktie well adapted to accomplish, among others, all of the objects 25 and advantages herein set forth.

Without further analysis the foregoing will so fully reveal the gist of this invention that others can by applying current knowledge readily adapt it for various applications 30 without omitting certain features that, from the standpoint of the prior art, fairly constitute essential characteristics of the generic or specific aspects of this invention, and therefore such adaptations should and are intended 35 to be comprehended within the meaning and range of equivalency of the following claim.

I claim:

In combination with a ready-made tie having a knot and neck encircling portions, 40 a forming and securing frame within said knot comprising an angular body of sheet material, the side portions of one member of said angular body being bent back to form a relatively thick frame with rounded outer 45 edges, the other member of said angular body terminating in a hook integrally formed with the frame and extending to one side, the top of which member is bent over to provide a rounded edge, and a member carried by the 50 neck encircling portion of the tie for cooperating with said hook.

Signed at Washington, D. C., this 7th day of February, 1929.

GEORGE AJDUKOVICH.
